(57) **CLAIM**

The ornamental design for a pair of motorcycle side bags, as shown and described.

DESCRIPTION

FIG. 1 is a rear view of a pair of motorcycle side bags showing our design;

FIG. 2 is a front view thereof;

FIG. 3 is a left side view thereof;

FIG. 4 is a right side view thereof;

FIG. 5 is a top view thereof; and,

FIG. 6 is a perspective view thereof.

The structure shown in broken lines does not form part of the claimed design.
